UNITED STATES PATENT OFFICE

2,679,112

CLOTHES DRIER

Ernest H. Thompson, Glenview, Ill.

Application June 30, 1951, Serial No. 234,497

9 Claims. (Cl. 34—53)

1

This invention relates to a clothes dryer and particularly one of small size adaptable for apartments and the like, the dryer including a housing which serves the additional purpose of a seat when it is not in use as a dryer for clothing and other laundry items, the design being such that the top of the dryer is approximately the height of a standard chair.

One object of the invention is to provide a clothes dryer which is comparatively inexpensive to manufacture, and which quickly and efficiently dries clothing in a perforated tumbling cylinder thereof located within the housing, the drying action being effected by the use of heated and circulated air.

Another object is to provide a clothes dryer to which access can be had by opening the top of the housing to gain access to a lid on the tumbling cylinder.

Still another object is to provide a clothes dryer of this general character in which the tumbling cylinder is driven by a small electric motor and air is circulated through the housing by a fan on the motor, the direction of circulation being preferably the same as the direction of rotation of the tumbling cylinder.

A further object is to provide a tumbling cylinder which can be manually rotated for positioning the lid thereof uppermost, for ready access to the interior of the cylinder for removing the dried clothing and inserting another batch of wet clothing, clutch means being provided for clutching the tumbling cylinder with respect to the driving motor therefor so as to permit of such manual rotation.

Still a further object is to provide a clothes dryer of the character disclosed having a tumbling cylinder which is readily removable so that lint can be readily cleaned therefrom and having a motor, fan and heater unit also removable for ready cleaning, the housing of the clothes dryer thereupon being accessible for cleaning lint therefrom while the tumbling cylinder and the unit are removed.

An additional object is to provide a clothes dryer which is small in size so as to require no more than the electric current permitted from the usual service outlet, the device being thus readily portable and capable of being plugged into any outlet in the home.

Another additional object is to provide a safety stop means on the tumbling cylinder to stop it from rotating in case the current is turned on before the lid of the tumbling cylinder is closed.

Still another additional object is to provide a

2

modified form of clothes dryer in which the tumbling cylinder motor may be controlled by a timer, and to provide a manually operable means for operating the motor again after the timer has stopped it yet it is desirable to rotate the cylinder sufficiently to bring the lid to uppermost position, the manual means then serving as a stop for the cylinder in such position.

A further additional object is to provide the modified form with a manually controllable means to energize the motor and at the same time loosen a drive belt for the tumbling cylinder to rotate the cylinder to the stopped position whereupon the manually operable means may be released which will again de-energize the motor and the cylinder will stay in the stopped position for removal of the clothing therefrom.

Still a further additional object is to provide a relatively inexpensive housing construction for clothes dryers and similar cabinet structures which may be formed of "insulating board" (such as those made of corn stalks or any suitable fibrous materials) in the form of panels which are secured together at the corners by novel fittings particularly adapted for this purpose, after which the walls of the housing and the fittings may be completely covered by a suitable covering material to provide a finished appearance.

With these and other objects in view, my invention consists in the construction, arrangement and combination of the various parts of my clothes dryer, whereby the objects contemplated are attained, as hereinafter more fully set forth, pointed out in my claims and illustrated in the accompanying drawings, wherein:

Figure 1 is a vertical sectional view through a clothes dryer embodying my present invention and showing the top open and the tumbling cylinder stopping means in the depressed position for stopping the cylinder.

Figure 2 is a horizontal sectional view on the line 2—2 of Figure 1.

Figure 3 is a vertical sectional view on the line 3—3 of Figure 1, the top being closed.

Figure 4 is a vertical sectional view on the line 4—4 of Figure 1, the top being closed in this figure also.

Figure 5 is a view similar to the upper right hand corner of Figure 1 showing the parts in the normal position when the clothing is being dried therein and the top is closed.

Figure 6 is an electrodiagrammatic view showing the motor and heating element, and a timer

switch therefor, together with an auxiliary switch operable by the cylinder stopping means.

Figure 7 is a vertical sectional view through a modified and preferred form of my invention, the cylinder thereof being shown in end elevation.

Figure 8 is a vertical sectional view on the line 8—8 of Figure 7.

Figure 9 is a horizontal sectional view on the line 9—9 of Figure 7.

Figure 10 is a vertical sectional view on the line 10—10 of Figure 9.

Figure 11 is a vertical detail sectional view on the line 11—11 of Figure 10.

Figure 12 is an enlarged vertical sectional view on the line 12—12 of Figure 10.

Figure 13 is a sectional view on the line 13—13 of Figure 12.

Figure 14 is a perspective view of a fitting for securing adjacent edges of panels of the dryer housing together; and

Figure 15 is a sectional view through two of the panels for forming the housing and showing one of the fittings of Figure 14 in installed position with the section being taken on the indicated line 15—15 of Figure 14.

On the accompanying drawings I have used the reference numeral 19 to indicate the bottom wall of a housing for my clothes dryer, 11 one end wall thereof, and 12 the other end wall thereof. These three walls, together with side walls 13 and 14, form a housing which is preferably of insulating material such as a molded plastic.

A top 15 is provided for the housing and it is shown relatively thick so that it is strong enough to support the weight of a person sitting thereon. The top 15 is preferably hinged as at 16 to the dryer housing, and the bottom wall 10 of the housing is provided with casters 17 for convenience in transporting the housing about the dwelling of the user.

A perforated cylinder 18 is provided in which there is a single projection 53 for tumbling the clothing. The cylinder 18 has end walls 19 which are journalled in bearings 20 and 21. A minor portion of the cylinder indicated at 22 serves as an openable lid for the cylinder and is hinged thereto as at 23. A hook 24 or the like may be provided to normally retain the lid 22 in the closed position.

A relatively large ring-like pulley 25 is secured to one end wall 19 of the tumbling cylinder 18 and a belt 26 extends around this pulley, through a slot 36a of the partition 36 and around a relatively small pulley 27. A pulley 28 is connected to the pulley 27 and a small belt 29 extends around the pulley 28 and around a pulley 30 mounted on the shaft 31 of a motor M. Also on the motor shaft is an air circulating fan 32.

The end wall 12 of the clothes dryer housing is hinged at 33 for convenience in gaining access to a heating element HE and the motor M together with the associated mechanism. The heating element is mounted on a partition 36 in which there is an opening 37. Also the end wall 12 has an opening 34 and it is screened as indicated at 35.

When the motor M is energized, the fan 32 thereof circulates air through the opening 34, 70 through the screen 35, past the heating element HE and through the opening 37 of the partition 36 as indicated by arrows in Figure 1, and this air travels around substantially the major portion of the cylinder 18 and in the direction of rotation 75

thereof. The moisture laden air is discharged through an opening 38 adjacent the top of the wall 12 which is provided with a screen 39.

Referring to Figure 6, a timer switch T is provided for the heating element HE and the motor M, the timer having separate circuits for these as indicated by the terminals h and m. The timer may be of the ordinary electrically or spring driven clockworks type to be set for a certain period of time sufficiently long to dry the charge of clothing deposited in the clothes dryer. At the end of the timing period it cuts off the current to both the heating element HE and the motor M. Line wires 41 and 42 are illustrated for energizing the motor and the heating element.

I provide an auxiliary switch 43 shunting the motor circuit of the timer T for a purpose which will hereinafter appear. Within the clothes dryer housing I provide a lever 43 pivoted at 44 and spring biased to the position of Figure 5 by a spring 45. A combined handle and stop 43a extends from one side of the lever 43. A belt tightening lever 46 is provided pivoted at 47 and having an idler pulley 48 carried thereby for normally engaging and tightening the belt 26 as in Figure 5 or loosening it as in Figure 1 if desired. The lever 46 is connected by a link 49 to the lever 43. The tumbling cylinder is provided with a projection 54 to strike the lever 43 as will hereinafter be described.

Referring to Figures 9 to 13, I show a modified and preferred form of my invention. The housing in this case consists of a bottom wall 56, end walls 57 and 58, a pair of side walls 60, and 35 a top 59 hinged as at 59a to one of the side walls 60.

Within the clothes dryer housing is a tumbling cylinder comprising a perforated cylindrical wall 61, a pair of cylinder sides 62, and a lid 63. The lid 63 in this instance is slidably mounted, lid slot 64 being provided in which the lid may be slid in a clockwise direction from the closed position of Figure 10 to an open position after a latch 65 on the cylinder is released.

The tumbling cylinder is removably mounted by means of a stud 66 projecting from the center of each side 62 of the cylinder and having thereon a bearing sleeve 67. The bearing sleeves are adapted to be received in notches 68 of bearing blocks 69 secured to the side walls 60 of the clothes dryer housing. Each stud has a head 70 thereon which is received in a head receiving slot 71 of its respective bearing block 69. This arrangement provides assurance that the bearings will be properly located for rotation of the studs 66 therein, yet the tumbling cylinder is readily removable for cleaning purposes.

For driving the tumbling cylinder I provide a motor M' having a shaft 72. The motor is pivoted at 73 and is biased to rotate about the pivot in a counter-clockwise direction in Figure 7 by a spring 74. A bolt 75 limits such rotation, the bolt traveling in a slot 76 of a bracket 77 that mounts the pivot 73 and thereby the motor M'.

The bracket 77 also has a pivot 78 for a clutch lever 79. The clutch lever is constrained to rotate counter-clockwise about the pivot 78 in Figure 7 by means of a spring 80. The clutch lever carries a shaft 81 on which is rotatably mounted a wheel 82. A friction tire 83 surrounds the wheel and is frictionally engaged by the motor shaft 72 under the action of the spring 74. The wheel 82 and tire 83 extend through a slot 86 in the unit housing 86.

An annular flange 84 is provided with attach-

ing ears 85 secured to one side 62 of the tumbling cylinder as shown in Figures 7 and 11. The friction tire 83 is biased by the spring 80 to contact with the annular flange 84 so that rotation is transmitted from the motor shaft 12 to the tumbling cylinder.

Within the clothes dryer housing, I provide a unit housing 86 which is removable in relation to the clothes dryer housing. Within this unit housing there is a blower housing 87 in which a blower 88 mounted on the motor shaft 12 is provided. The blower housing has an air intake 89 and it communicates with an intake screen 90 permanently mounted in the clothes dryer housing as shown particularly in Figure 9, arrows being used to indicate the path of the air inflow.

The blower housing 87 has an extension 91 serving as a reflector and this extension is doubled back as at 96 to provide a double-walled construction for heat insulating purposes. A pair of horizontal rods 92 extend transversely in the reflector housing formed by the reflector 91 and a pair of side walls 97 thereof shown in Figure 8. Other rods 93, vertically arranged, are secured to the rods 92 to form a heating element supporting framework. Brackets 94 are secured to the rods 93 for supporting insulating elements 95, and the heating element shown at HE is threaded through the insulators as shown in Figures 8 and 10. In front of the heating element is a screen 98 which is also part of the unit housing 86.

The unit housing 86 is merely set in the position shown and is retained in that location by studs 99a extending from the housing side walls 69 as shown in Figure 9, with one or two ears 99 provided with keyhole slots coacting with headed studs 100 extending from the end wall 58 as shown in Figure 10. Above the housing 86, a screen 101 is removably mounted, being held in position by a pair of flanges 102. The screen 101 is located inside another screen 103 which is permanently mounted in the wall 53 of the housing.

The tumbling cylinder of Figures 7 to 13, being somewhat larger in diameter than the one shown in Figures 1 to 6, is provided with two projections 104 for tumbling the clothing, and a baffle wall 105 spans one corner of the housing as shown in Figure 10 for increasing the efficiency of the circulated and heated air through the clothes being tumbled and dried.

On the tumbling cylinder, I mount a pivot stud 106 for a bell crank having arms 107 and 108. A spring 109 constrains the bell crank to rotate counter-clockwise in Figure 9, but when the lid 53 is slid completely closed and latched, it is rotated to the position shown against the bias of the spring. In case the lid is left partially or fully open, however, the spring 109 rotates the bell crank 107-108 to the dotted position so that any attempt to operate the clothes dryer will result in the arm 108 striking the stop 110 and thereby stopping rotation of the drum even though the motor M' continues to be energized. The motor will then either stall or continue to rotate with its shaft 12 slipping on the tire 83. If the arm 108 misses the stop 110, then it will strike the stop 111.

In Figures 14 and 15, I show how the panels that form the dryer housing may be formed and assembled by means of a special fitting 112. This fitting is made of sheet metal having a plate portion 113, a stop flange 114, and pairs of prongs 115 and 116. The prongs 115 extend at right

angles to the plate portion 113, while the prongs 116 are in the plane of the plate portion. The stop flange 114 extends at right angles to the plate portion 113 in a direction opposite the prongs 115 and from the edge of the plate portion 114 opposite the prongs 115.

The fitting 112, when thus formed, is suitable for securing the adjacent edges of two of the dryer housing walls together such as the walls 11 and 13 in Figure 15 with the face of one of the walls engaging the edge of the other wall. The plate portion 113 is then engaged against the face of the wall 13 with the stop flange 114 substantially flush with the end of the wall 13.

The prongs 115 are forced through the wall 13 (which may be formed of insulating board or the like) and clinched over on the bend lines 117 as at 115a, the clinch portion being preferably forced down into the material of the panel 13. The prongs 116 are then forced through the panel 11 and bend at the bend lines 117 to form the clinched parts 116a. Thus the adjacent edges of the panels are readily secured together in a rigid manner.

The entire housing may then be covered with a suitable cover material 118 on the inside, and 119 on the outside secured in position by adhesive or the like. The cover material may be imitation leather capable of standing the heat of the dryer, sheet plastic material, or any material suitable for the purpose.

Practical operation

In the operation of my clothes dryer, referring to Figure 1, it will be noted that the projection 53 has rotated to a position for engaging the clothing shown at 53a. It carries the clothing ahead of it to the dot-and-dash line position and only then does the clothing drop off, it being noted that the projection 53 is well above the center of rotation. The speed of rotation I select is one which causes the clothing to stay on the projection by centrifugal force until it reaches the dot-and-dash line position. In actual practice, I find anywhere from 40 to 60 R. P. M. suitable for this purpose.

The timer switch T is set for the desired time and when the time runs out, the heating element is de-energized and the motor is stopped. The lid 22, of course, may have stopped at any position and it is accordingly desirable to bring it around to the uppermost position. This is accomplished, after opening the top 15 to the position of Figure 1, by pressing downwardly on the handle 43a to move the lever 43 as indicated by the arrow 55 against the action of the spring 45 so that the lever 43 is in the path of the projection 54 on the cylinder 18, the handle 43a being stopped by engaging a partition 36a (see Figure 1). Accordingly, the motor M being now energized by closure of the switch 49, there will be sufficient traction between the loose belt 26 and the pulleys 27 and 25 to rotate the tumbling cylinder until the projection 54 strikes the lever 43. The cylinder 18 will thus be stopped in the position shown, whereupon the handle 43a may be released and the lid 22 may then be opened as to the dot-and-dash line position illustrated in this figure.

Since the timer has cut off the motor, however, the motor M must be re-energized by some other means to cause the drum to rotate to the stopped position. At the same time it is desirable to prevent energization of the heating element and also prevent positive rotation of the tumbling cylinder. This is accomplished by loosening the belt tightener to the position shown

in Figure 1 automatically through the link connection 49 when the lever 43 has been depressed and at that time energizing the motor which is accomplished by closure of the auxiliary switch 40.

In Figure 5 the belt tightener has been tightened under the action of the spring 45 when the lever 43 is released. At that time the switch 49 is reopened so that the motor is then back under the control of the timer switch T.

In the operation of my preferred form of invention shown in Figures 7 to 13, the motor M and the heating element HE may be connected to a current supply suitable cord that can be plugged into a service outlet whenever it is desirable to operate the clothes dryer. If desirable, a control switch may be provided in the circuit for the motor and/or the heating element.

The tumbling cylinder will rotate clockwise in Figures 7 and 10 and air will be circulated and heated by the blower 88 and the heating element HE, the direction of circulation being first through the screen 90, then past the heating element, then through the tumbling barrel, and finally out through the screens 101 and 103.

When the tumbling cylinder projections 104 reach approximately the position shown by dot-and-dash lines, the clothes will tumble from in front of the upper projection into position just ahead of the lower projection thus being effectively picked up and carried around to a position almost at the top of the drum before they tumble down again. During the carrying of the clothes, of course, some of them will start the tumbling action and the result is a spreading of the clothes substantially throughout the area in which the heated air is circulated, and the clothes are subject to radiant heat from the reflector 81 as well as the heating element HE, thereby quickly and efficiently drying them.

When it is desirable to remove the dried clothing and insert a wet batch, the top 59 is opened after the motor and the heating element are de-energized. If the lid 63 of the tumbling cylinder is not uppermost, the clutch lever 79 can be swung toward the right in Figure 7 for removing the friction tire 83 from contact with the annular flange 84 of the tumbling cylinder. The cylinder can then be readily rotated by hand until the lid 63 is uppermost so that it can be unlatched and slid back in its slots 64 for opening the cylinder to remove the clothing therefrom.

After a wet batch of clothing has been placed in the tumbling cylinder, the top 59 can be closed and the heating element and motor again energized for drying the same. In the event that the operator forgets to slide the lid 63 to a closed and latched position, or only partially closes it, then the bell crank 107-108 will be in the dotted position and the path of travel of the arm 108 will be close enough to the side wall 60 on which the stops 110 and 111 are mounted that it will engage one or the other of these stops, thus stopping the rotation of the cylinder. The operator, not hearing the rotation of the tumbling cylinder, will thus be apprised of the fact that the lid 63 has not been closed.

Either form of my invention will be found efficient in the drying operation and is particularly designed for providing a small compact clothes dryer especially adapted for apartment use and portability. At the same time the clothes dryer is one of the type that can be plugged into any service outlet, thus providing a clothes dryer in the nature of an electrical appliance as distinguished from a permanent installation. While

I have referred to my invention as a "clothes dryer," it is to be understood as adaptable for drying all laundry items and not limited to the drying of clothes only.

5 Some changes may be made in the construction and arrangement of the parts of my clothes dryer without departing from the real spirit and purpose of my invention, and it is my intention to cover by my claims any modified forms of 10 structure or use of mechanical equivalents which may be reasonably included within their scope.

I claim as my invention:

1. In a portable clothes dryer, a housing having an openable top, a perforated clothes tumbling cylinder rotatably mounted on a horizontal axis in said housing and having a minor portion of its periphery openable, said cylinder having clothing engaging means to engage and cause the clothing to tumble in said cylinder, means 15 for rotating said cylinder including an electric motor, a belt drive from said motor to said cylinder, a belt tightener therefor, means to stop the rotation of said cylinder at a position with said openable minor portion uppermost comprising a projection on said cylinder, a movable projection in said housing, and a connection between said movable projection and said belt tightener to loosen the tightener when said movable projection is moved to a position for engaging the projection of said cylinder.

2. In a clothes dryer, a housing, a perforated clothes tumbling cylinder rotatably mounted in said housing and having a portion of its periphery openable, means for rotating said cylinder including an electric motor, a belt drive from said motor to said cylinder, a belt tightener therefor, means to stop the rotation of said cylinder at a position with said openable portion uppermost comprising a projection on said cylinder, a movable projection in said housing, a switch for said motor, and a connection between said movable projection and said belt tightener to loosen the tightener and close said switch when said movable projection is moved to a position for engaging the projection of said cylinder.

3. A clothes dryer of the character disclosed comprising a housing having an openable top, a perforated clothes tumbling cylinder rotatably mounted in said housing and having a minor portion of its periphery openable, said cylinder having a clothes engaging projection therein, means for rotating said cylinder and for circulating heated air through said housing in a path around the major portion of the circumference of said cylinder and in the direction of rotation thereof, selective means for stopping the rotation of said cylinder in a predetermined position with said openable minor portion uppermost, a timer for stopping the operation of said motor, and means for energizing said motor selectively when stopping the rotation of said cylinder in order to cause it to rotate to the stopped position, said means including a belt tightener which is loosened when said selective means is operated.

4. In a clothes dryer, a housing, a perforated clothes tumbling cylinder rotatably mounted in said housing and having a portion of its periphery openable, said cylinder having clothing engaging means therein, means for rotating said cylinder including an electric motor, means for heating air, said electric motor having a fan for causing circulation thereof, a timer for said heating means and said motor, an auxiliary switch for operating said motor independent of 70 said timer, a belt drive from said motor to said

cylinder, a belt tightener therefor, and means to stop the rotation of said cylinder at a position with said openable portion uppermost comprising a projection on said cylinder, a movable projection in said housing, and a connection between said movable projection and said belt tightener to loosen the tightener when said movable projection is moved to a position for engaging the projection of said cylinder, said movable projection closing said auxiliary switch when it moves to a position for stopping said tumbling cylinder.

5. In a clothes dryer, a housing, a perforated clothes tumbling cylinder rotatably mounted in said housing and having a portion of its periphery openable, means for rotating said cylinder including an electric motor, a belt drive from said motor to said cylinder, a belt tightener therefor, a fan driven by said motor to circulate heated air through said cylinder, means to stop the rotation of said cylinder at a position with a said openable portion uppermost comprising a projection on said cylinder, a movable projection in said housing, and a connection between said movable projection and said belt tightener to loosen the tightener when said movable projection is moved to a position for engaging the projection of said cylinder.

6. In a clothes dryer, a housing having an openable top, a perforated clothes tumbling cylinder rotatably mounted on a horizontal axis in said housing and having a minor portion of its periphery openable, said cylinder having clothing engaging means to engage and cause the clothing to tumble in said cylinder, means for heating the air in said housing, means for rotating said cylinder including an electric motor, a timer switch for both of said means, a switch for energizing said rotating means independent of said heating means, means to stop the rotation of said cylinder at a position with said openable minor portion uppermost comprising a projection on said cylinder, a movable projection in said housing, and a connection between said movable projection and said switch to energize said rotating means when said movable projection is manually moved to a position for engaging the projection of said cylinder.

7. A clothes dryer of the character disclosed comprising a housing having an openable top, a perforated clothes tumbling cylinder rotatably mounted in said housing and having a portion of its periphery operable, said cylinder having a clothes engaging projection therein, means for rotating said cylinder and for circulating heated air through said housing, a stop for the rotation of said cylinder in a predetermined position with said openable portion uppermost, a timer for initially stopping the operation of said motor,

and means for energizing said motor independent of said timer and reducing the traction of the motor with respect to said cylinder in order to cause it to rotate yet be stopped by said stop.

5 8. In a clothes dryer, a housing, a perforated clothes tumbling cylinder rotatably mounted in said housing and having a portion of its periphery openable, said cylinder having clothing engaging means therein, means for rotating said cylinder including an electric motor, means for heating air, said electric motor having a fan for causing circulation thereof through said cylinder, a timer for said heating means and said motor, an auxiliary switch for operating said motor independent of said timer, a belt drive from said motor to said cylinder, a belt tightener therefor, means to stop the rotation of said cylinder at a position with said openable portion uppermost and a connection between said last means and said belt tightener to loosen the tightener when said last means is moved to a position for stopping said cylinder, said last means also closing said auxiliary switch at that time.

10 9. In a clothes dryer, a housing, a perforated clothes tumbling cylinder rotatably mounted in said housing and having a portion of its periphery openable, means for rotating said cylinder including an electric motor, a belt drive from said motor to said cylinder, a belt tightener therefor, a fan driven by said motor to circulate heated air through said cylinder, means to stop the rotation of said cylinder at a position with said openable portion uppermost, a switch for said motor, and a connection between said means and said belt tightener to loosen the tightener and close said switch when said means is operated to stop the rotation of said cylinder.
